(57) **CLAIM**

The ornamental design for a watchband having tool-free adjustment, as shown and described.

DESCRIPTION

FIG. 1 is a perspective view of a watchband having tool-free adjustment showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 2; and,

FIG. 10 is another partial enlarged view of FIG. 2.

The broken-line circle, which illustrates the boundary of the enlarged view shown in FIGS. 2, 9 and 10, and the broken-line arc in FIG. 2, together represent a detail callout. All other broken lines illustrate portions of the watchband. The broken lines form no part of the claimed design.
